FREDERICK A. DEPPERMAN, OF RIVERVALE, NEW JERSEY

FILM HANGER

Application filed April 30, 1931. Serial No. 534,081.

This invention relates to film hangers used in developing photographic films, the object being to provide an improved construction wherein the films are automatically held in place after having been properly inserted into the hanger.

Another object of the invention is to provide an improved hanger wherein the horizontal bars are all curved, two of which act to support the film and one to support the hanger in a container, while the respective hangers are nested.

A still further object of the invention is to provide a hanger with curved supporting members and straight supporting members arranged to automatically hold the film in place while exposing a maximum amount of surface to the developing, washing and fixing solutions.

20 Referring to the accompanying drawings—

Figure 1 indicates a hanger with a film thereon ready to be placed into a container.

Figure 2 is a sectional view through Figure 1 on line 2—2.

25 Figure 3 is a view similar to Figure 2 but showing the film only partly inserted.

Figure 4 is a fragmentary top view of a container and several hangers embodying the invention, the same being on a reduced scale 30 and illustrating how part of the hanger depends into the container and part extends across the top edge thereof.

Referring to the accompanying drawings by numerals, 1 and 2 indicate upright channel irons and 3 and 4 are what may be termed horizontal channel irons, the same being parallel with the supporting channel bar 5. Bar 5 is soldered, welded or otherwise rigidly secured to the uprights 1 and 2 but projects an appreciable distance therebeyond so as to rest on the top edges of the container 6 when the hanger is in use. The upright 1 is provided with a slot 7 for the full distance between the horizontal bars 3 and 4 whereby the film 8

45 may be readily inserted or removed. If desired, the film may be removed by bowing and without movement through the slot 7 though in loading the film it is desirable to insert the same through the slot 7. As the film is inserted through the slot 7, the top and bottom

edges will fit into the channel irons 3 and 4 and be guided thereby until the opposite end strikes the upright 2, whereupon the operator must push the edge 9 from the position shown in Figure 3 so that it may be slid into the 55 channel iron as illustrated in Figure 2. This movement of the film produces a tension as it warps the film. By reason of this tension, the edge 9 presses against the side wall 10 of upright 2 and the edge 11 presses against the 60 wall 12 of upright 1. The center of the film contacts at substantially point 13. In this way there is provided ample open space 14 whereby the walls may contact with the bottom and top edges of the film from post 1 to 65 post 2. If the sensitive side of the film is on the side of the space 14, it will be properly developed or otherwise treated from top to bottom and from the inner edge of the post 1 to the inner edge of post 2. If the opposite 70 side is the sensitive side, the entire surface of the film will be properly treated except at the point 13 on the respective bars 3 and 4 as these points contact with the bars 3 and 4.

The extensions 15 and 16 not only act as 75 means for supporting the hanger in a container, but act as handles for lifting up the hanger or manipulating the hanger in any desired way.

Recently there has been developed unusual- 80 ly sensitive films which must be loaded on the hanger in the dark, as ruby lights or other lights capable of being detected by the human eye will injure the film. When loading a hanger in an absolutely dark room, the op- 85 erator must be guided by his touch. Consequently, by having the hanger construction as specified, the operator may readily insert the film through slot 7 and then deflect edge 9 until it enters the upright 2 whereupon the 90 film is not only in proper place but is under some tension whereby it is automatically locked in place and does not come loose even when moved rather violently.

By curving the bars 5 in addition to bars 3 95 and 4, the same number of hangers may be placed in a container as heretofore. This structure which holds the films positively in place permits the operator to more or less agitate the solution during the treatment of 100

the film without danger of dislocating any of the films being treated. In this connection, it will be seen that the overhanging shoulder 16 as illustrated in Figure 2 will present an abutment whereby the film cannot readily move out of the opening 7.

I claim:

1. A film hanger comprising a frame having a pair of uprights extending beyond the frame, a supporting bar connected with said uprights, said uprights being substantially U-shaped in cross section, while the member connecting the uprights are bowed from one end to the other, said last mentioned members being formed with channels for the reception of film, said film being bowed by said members centrally and at the ends held straight by the uprights whereby a tension will be produced on the film to prevent accidental displacement thereof.
2. A film hanger including a supporting frame curved from one end to the other, said frame being formed with channel irons, one channel iron having a slot through which a film is adapted to be passed when loading the hanger, the curve of the frame causing a distortion of the film as it engages the respective ends and sides of the frame, the sides engaged in the curved part of the frame, the ends in the straight part, thus causing the ends to press against the straight part and thereby hold the film in the frame against accidental dislodgement.
3. A film hanger including a frame having a pair of uprights formed U-shaped in cross section, said uprights being straight, and a pair of side bars curved from one end to the other, each of said side bars being U-shaped in cross-section, one of said uprights having a slot extending from one side bar to the other and supporting means connected with said side bars and extending beyond the same.
4. A film hanger including a frame having a pair of uprights, one of said uprights having an opening through which the film is adapted to be inserted in the frame, said last mentioned upright having a shoulder adjacent the opening presenting an abutment for preventing the film from accidentally moving out through said opening.
